UNITED STATES PATENT OFFICE

GEORGE E. WEHRENBERG, OF CHICAGO, ILLINOIS, ASSIGNOR TO REGALITE, INC., OF CHICAGO, ILLINOIS, A CORPORATION OF ILLINOIS

DESIGN FOR A BEVERAGE DISPENSER

Application filed February 2, 1933. Serial No. 47,086. Term of patent 7 years.

To all whom it may concern:

Be it known that I, GEORGE E. WEHRENBERG, a citizen of the United States, residing at Chicago, in the county of Cook and State of Illinois, have invented a new, original, and ornamental Design for a Beverage Dispenser, of which the following is a specification, reference being had to the accompanying drawing, forming part thereof.

Fig. 1 is a front elevation of a beverage dispenser showing my new design;

Fig. 2 is a side elevation thereof;

Fig. 3 is a plan, and

Fig. 4 is a vertical fragmental longitudinal section taken on the line 4—4 and illustrating the contour of one of the shelves which forms part of the design.

I claim:

The ornamental design for a beverage dispenser server as shown and described.

GEO. E. WEHRENBERG.
